J. E. AMEND

CARBONATED MILK TANK

Filed Sept. 12, 1924

Inventor:
Joseph E. Amend
Atty:
Ervin B. Ciring
Attorneys:

UNITED STATES PATENT OFFICE.

JOSEPH E. AMEND, OF APPLETON, WISCONSIN.

CARBONATED-MILK TANK.

Application filed September 12, 1924. Serial No. 737,342.

To all whom it may concern:

Be it known that I, JOSEPH E. AMEND, a citizen of the United States, and resident of Appleton, in the county of Outagamie and State of Wisconsin, have invented certain new and useful Improvements in Carbonated-Milk Tanks; and I do hereby declare that the following is a full, clear, and exact description thereof.

10 This invention relates to tank construction and is particularly directed to a tank adapted for use with carbonated milk.

Tanks as heretofore made have not been satisfactory as it was impossible to clean them thoroughly and further as the block tin lining did not adequately cover the bolts, rivets or other devices of this general nature.

15 This invention is designed to overcome the above noted defects, and objects of this invention are to provide a tank for carbonated milk or similar liquids which is adequately lined with block tin, which is opened with the greatest ease to permit cleaning and washing of the interior of the tank, which may be closed in an air tight manner, and which is of simple and strong construction, and may be cheaply produced.

20 An embodiment of the invention is shown in the accompanying drawing, in which the single figure is a vertical sectional view through the tank.

The tank comprises an outer shell or tank proper 1 which may be of cast iron, wrought iron or any of the usual materials.

25 This tank is lined by means of a block tin lining 2 which completely covers the interior of the tank, and which has its end portions passed through the upper opening 3, and the large lower opening 4. The marginal portions of the block tin lining are folded outwardly, as indicated at 5 adjacent the upper end of the tank and are similarly folded outwardly, as indicated at 6 adjacent the lower end of the tank.

The lower end of the tank is provided, as stated, with a relatively large opening 4 which permits the free entry of the operator's hand or of a cleaning instrument, whereby the interior of the tank may be thoroughly washed or scrubbed.

30 A collar 7 provided with a flange 8 is secured to the tank 1 by any suitable fastening means such as the rivets 9. These

rivets 9 have their inner ends countersunk and headed, as indicated at 10, and in constructing the tank the heads are located below the block tin lining 2 so that such heads are thoroughly protected from contact with the carbonated milk. The collar 7 is internally threaded, as shown in the drawings, and it is to be noted particularly that the relatively soft block tin 6 provides a highly satisfactory gasket between the flange 8 of the collar and the corresponding face of the tank thus securing an air tight joint under all conditions.

35 A relatively large threaded plug 11 is screwed into the collar 7 and is provided with a block tin lining 12 across its upper face. This plug is suitably contoured to fit a wrench. For instance apertured ears 13 may be provided on its edge and a projecting squared boss 14 may be provided centrally thereof. It is to be understood, of course, that the plug may be contoured in other ways to fit the particular type of wrench used.

40 As is customary with this type of apparatus a pipe 15 extends downwardly into the tank to a point adjacent its lower portion. This pipe is provided with an enlarged upper threaded part 16 which is removably screwed into a flanged fitting 17, and held in place by a lock nut 18. Any suitable type of valve 19 may be provided at the upper end of the pipe. The fitting 17 is secured in the same manner as the collar 7, that is to say, its flanged portion is secured by means of rivets 20 to the tank 1 and the heads of the rivets are covered by the block tin lining on the inner side of the tank while the folded portion 5 of the block tin forms an effective gasket.

45 It is to be understood, of course, that the pipe 15 and the inner side of the fitting 17 are suitably tinned.

50 If desired the lower portion of the tank may be provided with a downwardly extending rim or flange 21 to protect the plug.

55 It will be seen that a tank has been provided which is lined throughout with block tin and which is equipped with a large aperture adjacent its lower portion whereby it may be most readily internally cleaned.

60 It will further be seen that although the tank is lined throughout with block tin that nevertheless a very effective removable

closure has been provided for the enlarged lower opening and thus the tank is eminently suited for the handling of carbonated milk, and may be most easily kept in a 5 highly sanitary condition.

Although the invention has been described in considerable detail, it is to be understood that the invention may be variously embodied and is, therefor, to be limited only as 10 claimed.

I claim:

1. A device for handling carbonated milk comprising a tank having a relatively large bottom opening adapted to permit the ready 15 cleaning of the interior of said tank and the entrance of an operator's hand, a block tin lining completely covering the interior of said tank and projecting through said opening and folded outwardly over the portions of said tank adjacent the margins of said opening, an internally threaded collar having a flange in contact with the folded portion of said block tin, rivets passing through 20 said flange and the adjacent portion of said tank and having their inner heads located within the tank and counter-sunk and covered by the block tin lining within the tank, a relatively large threaded plug removably 25 screwed into said collar, and a block tin lining for the upper face of said plug, said tank having a downwardly extending bottom flange projecting below the lower end of said plug.

block tin lining for the upper face of said 30 plug.

2. A device for handling carbonated milk comprising a tank having a relatively large bottom opening adapted to permit the ready 35 cleaning of the interior of said tank and the entrance of an operator's hand, a block tin lining completely covering the interior of said tank and projecting through said opening and folded outwardly over the portions of said tank adjacent the margins of 40 said opening, an internally threaded collar having a flange in contact with the folded portion of said block tin, rivets passing through said flange and the adjacent portion of said tank and having their inner heads located 45 within the tank and counter-sunk and covered by the block tin lining within the tank, a relatively large threaded plug removably screwed into said collar, and a block tin lining for the upper face of said plug, said 50 tank having a downwardly extending bottom flange projecting below the lower end of said plug.

In testimony that I claim the foregoing I have hereunto set my hand at Appleton, 55 in the county of Outagamie and State of Wisconsin.

JOSEPH E. AMEND.
